(57) **CLAIM**

The ornamental design for a table lamp, as shown and described.

DESCRIPTION

1. Table lamp

The figure 1.8 represents the lamp with the light on; the light reflection and the shade on the reproductions are for illustrative purposes only and form no part of the claimed designs; fig. 1.1 is a perspective view of the design; fig. 1.2 is a front view thereof; fig. 1.3 is a rear view thereof; fig. 1.4 is a right view thereof; fig. 1.5 is a left view thereof; fig. 1.6 is a top view thereof; fig. 1.7 is a bottom view thereof; fig. 1.8 is a perspective view of the design with the light on. The portion of the cord shown in figs. 1.4-1.7 is abbreviated for purposes of illustration; the claimed portion of the cord is fully shown in fig. 1.1 and fig. 1.8.

1 Claim, 8 Drawing Sheets(56)
